US0D1022597S

(12) United States Design Patent (10) Patent No.: US D1,022,597 S
(45) Date of Patent: * Apr. 16, 2024

(54) CONTAINER LID

(71) Applicant: YETI Coolers, LLC, Austin, TX (US)

(72) Inventors: Roy Joseph Seiders, Austin, TX (US);
Steve Charles Nichols, Austin, TX (US)

(73) Assignee: YETI Coolers, LLC, Austin, TX (US)

() Term: 15 Years

(21) Appl. No.: 29/737,329

(22) Filed: Jun. 8, 2020

Related U.S. Application Data

(63) Continuation of application No. 29/634,477, filed on Jan. 22, 2018, now Pat. No. Des. 886,526, which is a continuation of application No. 29/558,203, filed on Mar. 15, 2016, now Pat. No. Des. 808,218, which is a continuation of application No. 29/544,618, filed on Nov. 4, 2015, now Pat. No. Des. 751,341.

CLAIM

The ornamental design for a container lid, as shown and described.

DESCRIPTION

FIG. 1 is a top, front, right perspective view of a container lid showing our new design;

FIG. 2 is a front view thereof;

FIG. 3 is a rear view thereof;

FIG. 4 is a right side view thereof, wherein the left side view is a mirror image of FIG. 4;

FIG. 5 is a top view thereof;

FIG. 6 is a bottom view thereof; and,

FIG. 7 is a top, front, right perspective view of a container lid showing our new design in an alternate closed position. The broken lines in the drawings depict portions of the container lid that form no part of the claimed design.

1 Claim, 6 Drawing Sheets
